US00D757106S

(12) **United States Design Patent**
Patel et al.

(10) **Patent No.:** **US D757,106 S**
(45) **Date of Patent:** **** May 24, 2016**

(54) **DISPLAY SCREEN WITH GRAPHICAL USER INTERFACE**

(71) Applicant: **Microsoft Corporation**, Redmond, WA (US)

(72) Inventors: **Amish Patel**, Seattle, WA (US); **Daniel Edward Ostrowski**, Seattle, WA (US); **Michael Tedesco**, Sammamish, WA (US); **Larry Russell Butcher**, Seattle, WA (US)

(73) Assignee: **Microsoft Corporation**, Redmond, WA (US)

(**) Term: **14 Years**

(21) Appl. No.: **29/492,469**

(22) Filed: **May 30, 2014**

(51) LOC (10) Cl. **14-04**

(52) U.S. Cl.

USPC **D14/492**

(58) **Field of Classification Search**

USPC **D14/485-495**

See application file for complete search history.

(57) **CLAIM**

The ornamental design for a display screen with graphical user interface, as shown and described.

DESCRIPTION

The sole FIGURE is a front view of a display screen with graphical user interface showing our new design.

The broken line rectangle showing of the display screen is included for the purpose of illustrating portions of the article and forms no part of the claimed design.

1 Claim, 1 Drawing Sheet
